UNITED STATES PATENT OFFICE.

HERBERT L. WILLIAMS, OF EVERETT, WASHINGTON, ASSIGNOR OF ONE-HALF TO
PERCY E. AMES, OF EVERETT, WASHINGTON.

LOGGING-BUNK.

1,108,416.

Specification of Letters Patent. Patented Aug. 25, 1914.

Application filed May 18, 1914. Serial No. 839,223.

To all whom it may concern:

Be it known that I, HERBERT L. WILLIAMS, a citizen of the United States, residing at Everett, in the county of Snohomish, State 5 of Washington, have invented a new and useful Improvement in Logging-Bunks, of which the following is a specification.

My invention relates to an improvement in logging bunks and stakes therefor, and 10 comprises the novel features which will be hereinafter defined by the claims.

One object of my invention is to provide a bunk of a shape and material such that it 15 will be strong for the amount of material therein, will securely hold the logs in the position in which they are placed thereon and one which will not collect or hold dirt, and one in which the movable parts are 20 protected against clogging or interference by dirt or rubbish.

Another object of my invention is to provide an improved type of logging bunk and therewith a chock which may be used in many cases without other means for holding 25 the logs in place on the bunk, and also means for holding this chock against release, and whereby the same may be quickly and safely released from the opposite side of the car.

30 A further object of my invention is to provide a strong and efficient type of stake for use in connection with said bunk, which may be released for the discharge of the load by the act of tripping the chock.

35 Other objects of the invention will be brought out in the specification and claims.

In the accompanying drawings I have shown my invention in the form which is now preferred by me.

40 Figure 1 is a longitudinal sectional elevation of the bunk and chocks, the central portion being cut away to shorten the figure. Fig. 2 is a transverse sectional elevation, taken through the central part of the bunk.

45 Fig. 3 is an end elevation of the bunk with the chock removed. Fig. 4 is a sectional longitudinal elevation of one end of a bunk, taken just at one side of the chock. Fig. 5 is a side elevation of a bunk, showing the 50 chocks in raised position, and stakes in use therewith. Fig. 6 is an end elevation of a bunk with a stake thereon.

The bunk 1 as herein shown, is supposed to be made of metal, preferably a steel cast-

ing, and in the major part of its length has 55 an inverted V-shaped cross section, as is clearly shown in Fig. 2. Flanges 11 at the ends of each arm of the V, serve as a base. The sides or arms 10 are preferably slightly curved, the convex side being outward, and 60 at their point of junction the curve of the sides becomes a straight line, forming a sharp apex 12, upon which the logs rest. This sharp upper edge will tend to cut 65 slightly into the logs and thus hold them securely against sliding transversely of the bunk and longitudinally of the logs. At each end of the bunk its upper line is cut down or lowered slightly, and the sides separated at the top forming vertical flat 70 sides or flanges 13.

Between the side walls of the bunk, at each end at about the point where the triangular section merges into the flat vertical walls 13, is pivoted a chock 2. The pivot 75 pin 20 of this chock is supported in short slots 21 in the side walls of the bunk, whereby the chock may have a slight bodily movement lengthwise the bunk, while this part of the chock is held against vertical movements. The chock in the preferred form shown, has side walls 22, an upper and inner face wall 23, which connects said side walls, and an outwardly curved face wall 24, which is made as an arc of a circle with the pivot 80 pin as a center. The lower edge 25, of this outer wall of the chock, rests and is supported when in raised position upon a surface 17 at the upper edge of an upwardly projecting portion 16 at the outer end of the 90 bunk. This portion 16 is supported by webs or plates 18 which are spaced inward from the side walls 13 so as to leave slots 14 between the two, of such width as will receive the side walls 22 of the chock. The 95 parts 16 and 18 taken together, constitute what might be called an upwardly projecting horn. Its function is to act as a support for the chock when the chock is in its innermost and raised position, as shown at 100 the left in Fig. 1 and in Fig. 4. If the chock be moved outwardly a sufficient distance to carry the outer curved wall 24 beyond the outer end of horn 16, the chock will no longer be thereby supported in elevated 105 position, but will drop to the position shown at the right in Fig. 1, in which position the side walls 22 have dropped into the slots 14,

and the uppermost part of the chock has dropped below the upper edge of the bunk. In this position the logs which may have been supported on the bunk are no longer restrained by the chock, and may freely roll off the bunk.

In addition to the above means for supporting the chock, or as a substitute therefor if this be desired, I provide a slot 7 in the inner surface of the side walls 13, into which fit lugs or projections 71 carried by the outer lower corner of the chock. These grooves 7 terminate at their upper ends in inward extensions 70 into which the lugs 71 of the chock enter when the chock is drawn inwardly thereby acting to hold the chocks in raised position until it is shifted outwardly. The surfaces which hold up the outer ends of the chocks should preferably be somewhat inclined, so that the chocks will promptly slide off as soon as their holding rods 3 are released.

A rod 3 is connected by one end with the pivot pin 20 of the chock. This rod extends within the chamber inclosed between the side walls of the bunk to its opposite end. Here it is provided with a lateral offset or tooth 30, upon its lower side, which offset is in such horizontal position that when the chock 30 is in its innermost or raised position, this offset will enter and engage the vertical face 31 of a recess 32, which is formed in the end of the bunk. This recess is of such vertical depth that there will always be sufficient space between the end of the rod 3 and the horizontal bottom 33, into which to insert a bar, and thereby pry up this end of the rod 3. Preferably the extreme end of the rod 3 should project somewhat beyond the outer end of the bottom 33 of said recess, whereby a hammer or stone may be used to pound up this end of the rod, if it be necessary or more convenient to release it in this manner. The projection of this end of the rod should, however, be short enough that the chock 2 at this end may pass over the outer end thereof, or into the position shown at the right in Fig. 1.

The rod 3 may be locked in its holding position, or that shown at the right in Fig. 1, by means of a dog 4 which pivots upon a pin 40 which is cast integral with the horn 16. The dog 4 is a split dog having its parts secured together after being put in place. This may be engaged to throw it up prior to releasing the rod 3 and will drop into locking position by gravity. By throwing this dog into upper or horizontal position, as is shown at the left in Fig. 1, the chock holding arm 3 may have its end raised enough to clear its offset or tooth 30 from the holding face 31 of the bunk, thereby releasing the chock which is connected therewith.

In connection with this type of chock and

bunk, I provide a stake which is shown in Figs. 5 and 6. This stake is so constructed that at its lower end it has two separated bars 50, spaced so as to fit over the ends of the bunk. It is also provided with lugs, 70 ears, or an equivalent transverse extension, at 51, so placed that when the lower end of the stake is in its proper position on the bunk, these lugs 51 will be in engagement with the upper portion of the inner upper 75 face 23 of the chock. The lower ends of the stakes are held in place by means which form a part of the bunk, and which form a pivotal connection, whereby the stake may be swung outwardly and downwardly. In 80 the form of construction shown at the right hand in Fig. 5 this constitutes a pivot pin and the stake is fixedly secured thereby to the bunk. In the form of construction shown at the left in Fig. 5 two lugs, 6 and 85 60, are provided at the side of the bunk, between which the ends of the stake are placed, thereby preventing movement of this end in a direction lengthwise the bunk. The shape of these lugs and their size is 90 such that the outwardly and downwardly swinging movement of the stake will not be interfered with. Preferably the inner lower corner of the arms 50 of the stake should be rounded, as shown at 53, to further facilitate the swinging action of the stake, when the construction shown at the left in Fig. 5 is used. When this type of construction is used, I prefer that the stake be connected with the bunk so as to prevent separation, 105 as by means of a short chain 55. The relative location of the pivoting point for the stake and for the chock is such that the stake is quickly pushed off the chock after movement commences, thus freeing their 110 connection. To prevent the stake from swinging too far inwardly, it may be provided with a stirrup 54 which embraces the outer surface of the chock. When the stake is fixedly pivoted on the bunk it may be secured in lowered position when desired by means of a link or hook, as shown at 56, whereby the stake is secured to a member of the car frame.

The downwardly projecting portion 34 at 115 the ends of the bunk, form an abutment or ear which engages the outer surface of a beam 35 which forms a portion of the framing of the car. This holds the bunk securely in place on the car frame.

It will be seen that the log retaining members, the chocks and stakes, are supported by two bearings which are separated lengthwise the bunk, these consisting of the pivots 20 and the bearings at 25-17, the inner of 120 these, or the pivot 20, being held against vertical movements, either up or down, while the other, 25-17, is held against downward movement until the chock is moved outward enough to bring these sur- 125 130

faces out of engagement, in which case only, can the chock give way and fall down. The outward movement of the chock, when its holding mechanism is released, is assisted by 5 an inclination of the supporting surfaces 25-17. This outward movement is resisted by the rods 3 which are strained under tension only and hence can be made amply strong with medium weight. Moreover, 10 these rods do not have to resist the actual force applied to the chocks or stakes, but only to resist sliding of the chock outward upon the bunk, which is a much lighter strain. The design of these parts is such 15 that they may be made amply strong to resist any strain to which it is reasonable to expect they will be subjected. The sharp upper edge of the bunk causes it to bite into the logs and hold them securely against 20 lengthwise movement. The hollow shape accommodates the chock releasing and holding mechanism and protects it from dirt. Being open at the bottom, any dirt which 25 may enter will be at once discharged. The triangular section of the bunk is also one which is very strong for a given weight.

I claim as my invention—

1. A logging bunk composed of two diverging webs joined along one edge and 30 forming a sharp apex, the base of said angle being open.

2. A logging bunk composed of two diverging plates or webs joined along one edge and forming a sharp apex, said webs being 35 slightly convexed outwardly.

3. A logging bunk composed of two diverging webs joined along one edge, the separated edges of said webs being disconnected and having outwardly extending 40 bearing flanges.

4. A logging bunk composed of two diverging webs connected along one edge, said webs being convexed outwardly and terminating at the apex in flat planes.

45 5. A logging bunk having a cross section of an inverted V-shape terminating in a sharp upper edge.

6. A logging bunk having a cross section of an inverted V-shape terminating in a sharp upper edge and having chock receiving recesses in its ends.

50 7. A logging bunk having a cross section of an inverted V-shape, chocks mounted on its ends to drop down, means for holding 55 the chocks in elevated position and controlling members therefor extending within the space between the sides of the V to the opposite ends of the bunk.

8. The combination with a logging bunk 60 of a chock block having its inner end pivoted upon the bunk and capable of a limited movement lengthwise the bunk, the outer end of the chock and the bunk having surfaces engaging to support the chock when 65 the latter is in its innermost position and

disengaging when in its outermost position, and means for controlling the longitudinal position of the chock upon the bunk.

9. The combination with a logging bunk 70 of a chock block having its inner end pivoted upon the bunk and capable of a limited movement lengthwise the bunk, the outer end of the chock and the bunk having surfaces engaging to support the chock when the latter is in its innermost position and disengaging when the chock is in its outermost position, a rod connected at one end with the chock and extending to the opposite end of the bunk, and means for locking 75 said rod controlled from the opposite end of the bunk.

10. The combination with a logging bunk 80 of a chock block having its inner end pivoted upon the bunk and capable of a limited movement lengthwise the bunk, the outer end of the chock and the bunk having surfaces engaging to support the chock when the latter is in its innermost position and disengaging when the chock is in its outermost position, means for locking the chock 85 block in its innermost position and means for releasing said lock from the opposite end of the bunk.

11. The combination with a logging bunk 90 of a chock block having its inner end pivoted upon the bunk and capable of a limited movement lengthwise the bunk, the outer end of the chock and the bunk having surfaces engaging to support the chock when the latter is in its innermost position and disengaging when the chock is in its outermost position, a rod connected with the chock pivot and extending to the opposite end of the bunk, said opposite end of the 95 rod having a side tooth or offset and the bunk having a shoulder for engagement therewith when the chock is in its innermost position, and manually releasable means for holding down this end of said rod.

12. The combination with a logging bunk 100 of a chock block having its inner end pivoted upon the bunk and capable of a limited movement lengthwise the bunk, the outer end of the chock and the bunk having surfaces engaging to support the chock when the latter is in its innermost position and disengaging when the chock is in its outermost position, a rod connected with the chock pivot and extending to the opposite end of the bunk, said opposite end of the 105 rod having a side tooth or offset and the bunk having a shoulder for engagement therewith when the chock is in its innermost position, and a rotative bar having a lateral projection adapted to engage and hold down said opposite end of the rod.

13. The combination with a logging bunk 110 of a chock block having its inner end pivotally supported from the bunk and capable of a limited movement lengthwise the bunk, 115

the bunk and chock having surfaces engaging to support the chock in elevated position when the chock is in its innermost position, said surfaces being inclined to induce an 5 outward sliding tendency in the chock, and manually releasable means for holding the chock in its innermost position.

14. The combination with a logging bunk having a horn-like projection of a chock 10 block pivoted by its inner end upon the bunk and capable of limited movement lengthwise of the bunk, the chock having a recess adapted to receive said horn when the chock is in its outermost position and the chock 15 when in its innermost position being supported by the horn.

15. The combination with a logging bunk having a chock supporting horn separated at its sides from other parts of the bunk to 20 form free spaces, of a chock block having its inner ends connected to the bunk by a pivot capable of a limited movement lengthwise the bunk, said chock having side walls separated to correspond to the location of the 25 free spaces at the sides of the horn and hav-

ing a member connecting said side walls and adapted to rest on and be supported by the outermost portion of the upper surface of the horn, whereby when in its outermost position the chock may drop over the supporting horn. 30

16. The combination with a logging bunk, chock blocks pivoted at the ends of the bunk to drop outward and down, means for holding and for releasing said chocks, stakes 35 having a pivotal engagement with the bunk outwardly of the pivots for the chocks and having a part adapted to engage the inner face of the chock in its upper part.

17. The combination with a logging bunk 40 of chocks and means for holding the chocks in raised position, of stakes having a pivotal engagement at their lower ends with the bunk and a supporting engagement with the inner surface of the chocks, and means for 45 tripping the chocks.

HERBERT L. WILLIAMS.
